UNITED STATES PATENT OFFICE

2,573,160

FIRE DOOR

August Olaf Norman, West Nyack, N. Y.

Application May 5, 1947, Serial No. 745,989.

2 Claims. (Cl. 189—47)

1

This invention relates to an automatic door and more particularly to slidable doors adapted for automatic closure in the event of fire or other emergency.

Prior to this invention most slidable fire doors were automatically operated by the melting of a fusible element due to the heat of the fire. This device was limited to fires only and could not be operated for example where a smoldering fire emitted obnoxious fumes or smoke which do not furnish sufficient heat to melt the fusible element. Thus, the door would remain open while the fumes and smoke spread to other areas of the building.

In addition, when said fusible element was melted accidentally by a workman's blow torch which may heat metal near said door and thus conduct sufficient heat to the fusible element, said door would remain inoperative until a new fusible link had replaced the melted one. Any delay in obtaining the substitute fusible link may leave said building unprotected by said fireproof door.

It is therefore the main object of this invention to provide an electronically controlled sliding door which may be controlled automatically and manually by remote control.

Another object of this invention is to provide an electronically controlled sliding door which may be reset for future operation immediately after said door has been operated to the closed position by accidental use of the activating element. This can be done without the replacement of any operating part of said door.

Still a further object of this invention is to provide a slidable fire door which has a closable opening which may be used for inserting a fire hose through said door into the room containing the fire.

Other objects and advantages will appear from the following description considered in connection with the accompanying drawings, in which:

Figure 1 is an elevational sectional view of the fire door in the open position showing it held within a recess provided for it in the wall;

Figure 2 is a view of the fire door of Fig. 1, showing the fire door in the closed position when danger occurs;

Figure 3 is a longitudinal sectional view of the fire door shown in Figure 1, taken along the lines 3—3;

Figure 4 is a cross-sectional view of the door handles of the fire door shown in Fig. 2 taken along line 4—4; and

2

Figure 5 is a side elevational view of the closed door.

Referring now to the drawings and in particular to the automatic fire door shown in Figures 1 and 2, and also, in Figure 3, this fire door comprises a slidable door frame 1 which is composed of two outer panels 2 and 3 with an air space 4 between them. Said door frame air space 4 is closed at the front end 5 and opened 10 at the rear end 6 to permit movement of the activating mechanisms which will be hereinafter described.

A channel 7 is cut into the wall 8 which is aligned with the door opening 9. Said channel 15 7 is sufficiently wide to permit said door frame 1 to slide completely within said channel 7.

Attached to the roof 10 and floor 11 of said channel 7 are guide rails 12 and 13 respectively. A pair of aligned wheels 14 are attached by 20 brackets 15 to the inside central portion of top and bottom of the door frame 1 so that said wheels 14 are aligned with said guide rails 12 and 13 and are adapted to roll along said guide rails 12 when said door frame 1 is pushed into 25 or out of said wall 8. Attached to the rear wall 16 of said channel 7 are a pair of solenoids 17 and 18 which are arranged one above the other. Said solenoids 17 and 18 comprise supporting brackets 19 and 20, plungers 21 having right 30 angle catch pins 22 at one end, fixed washers 23 around the centers of said plungers 21, and springs 24 surrounding said solenoids 17 and 18 and compressed between said washers 23 and electronically controlled solenoid latches 25, 35 which are adapted to catch pins 26 on the lower parts of said plungers 21 when said plungers 21 are driven down by the opening door.

A pair of catch hooks 27 and 28 are attached by means of bolts 29 to the outer rear panel 30, 40 of said sliding door frame 1. Said catch hooks 27 and 28 have an extended inclined straight rod 31 and a hooked rod 32 with said inclined straight rod 31 positioned slightly above said hooked rod 32. Said catch hooks 27 and 28 are so positioned 45 that when said fire door is slid back into the channel 7 of the wall 8, said inclined straight rod 31 strikes against the catch pins 22 located at the end of said plungers 21 and drives said plungers 21 downward until the catch pins 26 engage the solenoid latches 25, thus holding the upper pins 22 within the curve of the hooked rods 32 of said catch hooks 27 and 28, respectively.

At substantially the center of said rear wall 16 of said channel 7 of the wall 8, is attached a 55 supporting bracket 33 having an aperture 34.

therein adapted to receive the closed end of a cylinder 35 which is supported in a centrally horizontal position along the walls of the channel 7 by means of brackets 36 which are attached to said cylinder 35.

A piston 37 having a piston valve 38 at one end 39 is adapted to slide within said cylinder 35. The other end 40 of said piston 37 is attached to a flange 41 which is in turn affixed to the central part of the front 5 of said door frame 1.

Paired rods 42 and 43, respectively, are arranged in the form of a double toggle joint by pivotally joining the ends 44 of said rods 42 to a pivot 45 while the other ends 46 of said rods 42 are pivotally attached to pins 46 set in the door flange 41 and pins 47 set in the cylinder bracket 36. Rods 43 are similarly attached in opposing piston on the under side of the cylinder 35. A pair of springs 48 are attached between said pins 45 by means of hooked ends 49.

An opening 50 is placed in said door for insertion of a fire hose through said door into the burning room. A pair of covers 51 operated by a handle 52 and a lever rod 53 are adapted to open and close said opening 50 in the door. Said handles 52 are attached pivotally within recesses provided for them on the outside of said door frame 1 so that they won't interfere with the movement of the door within the channel 7 of the wall 8. Said covers 52 are arranged against the inside walls 2 and 3 of the door frame 1.

Referring now to Fig. 4, a pair of handles 54 and 55 are pivotally attached by means of recessed brackets 56 and 57, respectively, to the front part of the walls 2 and 3 of said door frame 1. A spring 58 is attached between the projecting pivotal ends 59 of the handles 54 and 55 so that said handles 54 and 55 project outwardly for easy grasping when said door is closed. However, when said door is slid into the channel 7 of the wall 8, said handles 54 and 55 strike against the side walls 8 and are compressed inwardly against the recessed brackets 56 and 57, respectively, as shown by the dotted lines in Figure 4.

Suitable size holes 60 are placed in the inside of the cylinder 35 of the speed control equipment so that when said piston 37 is forced out of the cylinder by means of the spring loaded toggle joint pressure, said piston valve 38 will be held back by the decreased air pressure within said cylinder 35. The amount of vacuum appearing within said cylinder is regulated by these air holes 60 and will therefore regulate the speed of the closing mechanism in proportion to the amount of air admitted by said holes 60.

The operation of the device is as follows:

An electronically controlled fire alarm system, such as one activated by thermostatic control or a compound bar contact arrangements whereby excessive heat may close a contact which in turn would close any suitable electronic relay or activating device, releases the solenoid catch 25 shown in Figures 1 and 2. These electronically controlled fire devices may be placed in any suitable location within the room to be protected. For example, a thermostatic control or fire sensitive compound bar contact may be arranged in strategic positions near said fire door or they may be placed in any position near the ceiling in the staggered position of a sprinkler system. In addition, said electronically controlled solenoid catch may be released by remote control from any fire station within said building when either fumes or smoke are detected in the building. In such case, any person in charge of the fire sta-

tion could operate any or all fire doors by pressing appropriate buttons or turning appropriate switches which would thus release the solenoid catch 25 and permit said fire doors to be closed by the spring activated double toggle joints as hereinbefore described. However, should the heat in said protected room rise above the danger limit which may be due to any type of fire, said sensitive compound bars nearest to said fire would close and thus operate the solenoid catch to the open position, which would in turn release the fire door and thus seal off the opening to the burning room. Should any of the thermostatic controls or compound bar contacts be accidentally activated which would result in the closing of the fire door, said fire door may be easily pulled again to the open position and retained in such open position without replacing any of the fire controls as would be the case when fusible links or elements are used. In the operation of this embodiment, release of the solenoid catch 25 permits the solenoid spring 24 to push the solenoid plunger in an upward direction. The pin 22 at the end of said solenoid plunger 21 will be raised above the hooked portion 32 of the hook element 28, thus releasing said hooked element 28 from said solenoid pin 22. The springs 48 will be held between the toggle joints 48, and will be compressed and thus force the slideable door 30 across the door opening until the front portion 5 of said slideable door strikes against the frame of said door opening. In addition, an opening 50 is provided in said door frame 1 for insertion of a fire hose to flood down the burning room. The cover 51 may be removed from said opening 50 for fire hose purposes as mentioned above, by rotating the handle 52 which is pivotally mounted so that it can be raised out of the recessed opening 54 into which it is placed when not in use. By rotating said handle 52, lever 53 is propelled in such a fashion that the cover 51 is moved clear away from the opening 50. This exposure of the opening 50 may be done either from the side of the closed door, as shown by the sectional view 35 of the fire door in Figure 3. The spring loaded handles 54 are pivotally mounted so that when said sliding door is in the closed position, the spring 58 compresses the pivoted ends 59 and the handles are tilted out of the recessed openings in 40 the door. These handles 54 are used for opening the door and sliding it back to the open position.

It will be noted that when said slideable door is pulled into the channel 7 of the wall 8, said 55 spring loaded handles 54 will abut against the frame of the channel 7 and thus be compressed into the recessed plate provided for them. These handles 54 may be operated from either side of the door.

60 The evident advantage of this type of electronically controlled fire door is that the door may be operated to protect parts of a building from obnoxious fumes, smoke and other fire hazards.

65 The closing speed of said fire door can be easily regulated by increasing or decreasing the vacuum effect on the piston 37 and piston valve 38 within said cylinder 35 by a predetermined size of a series of holes which permit the outside air to 70 flow into and out of said cylinder 35.

As will be seen from the above description, the invention discloses an electronically controlled sliding fire door which may be controlled automatically and manually by remote control. In 75 addition, this electronically controlled sliding

door is novel in that it may be reset for future operation after said door has been accidentally operated to the closed position without replacing any of the activating elements. The unusual feature of a closable opening which may be used for inserting fire hose therethrough makes this fire door an additional safeguard for fire fighting purposes.

While in disclosing the principles of my invention and its preferred embodiment, I have described various detailed structure and relationship, it will be understood that such embodiment and details are given by way of example only and not as limiting the scope of my invention.

Having thus described my invention, what I claim and desire to secure by Letters Patent, is:

1. A fire door assembly comprising a frame, a hollow fire door slidably mounted in the frame, a rigid horizontal tubular brace member having one end fixedly secured to a side of the door frame and extending within the interior of the door, a piston and piston rod connected thereto within the tubular brace member, means securing one end of the piston rod to the door, a first set of lever arms each pivotally connected at one end to the tubular brace member, a second set of lever arms each pivotally connected at one end to the interior of the door, means pivotally connecting each of the other ends of the second set of lever arms to a respective one of the other ends of said first set of lever arms, spring means connecting the mutually pivoted ends of said lever arms for biasing the latter and the door toward a closed position, a latch element carried by the door, and means coacting with said latch element to hold the door in open position against the action of said spring means, said coacting means being operable from a point exterior of the door frame, whereby said tubular brace member serves both as a means for mounting said lever arms within the interior of the door and also as an element cooperating with said piston and piston rod to form a door check means.

2. A fire door assembly comprising a frame, a hollow fire door slidably mounted in the frame, a rigid horizontal tubular brace member having

one end fixedly secured to a side of the door frame and extending within the interior of the door, a piston and piston rod connected thereto within the tubular brace member, means securing one end of the piston rod to the door, lever means within the interior of the door and pivotally connected at one end to said tubular brace member and at the other end to the door, said lever means being actionable to react against said tubular brace member and move said door toward a closed position, spring means for actuating said lever means so as to bias said lever means and said door toward a closed position, a latch element carried by the door, and means coacting with said latch element to hold the door in open position against the action of said spring means, said coacting means being operable from a point exterior of the door frame, whereby said tubular brace member serves both as a means for mounting said lever means within the interior of the door and also as an element cooperating with said piston and piston rod to form a door check means.

AUGUST OLAF NORMAN.
